CLAIM

The ornamental design for an automobile, as shown and described.

DESCRIPTION

FIG. 1 is a top, front and left side perspective view of an automobile showing my new design;

FIG. 2 is a top, rear and left side perspective view thereof;

FIG. 3 is a left view thereof;

FIG. 4 is a top plan view thereof;

FIG. 5 is a left side elevational view thereof;

FIG. 6 is a rear elevational view thereof; and,

FIG. 7 is a right side elevational view thereof.

The broken lines in the drawings illustrate portions of the automobile that forms no part of the claimed design.
